[57] CLAIM

The ornamental design for an earring, as shown and described.

DESCRIPTION

FIG. 1 is a front perspective view of an earring showing my new design.

FIG. 2 is a left side view of the earring of my design, the right side view being a mirror image of the left side view.

FIG. 3 is a top view of the earring of my design, the bottom view being a mirror image of the top view.

FIG. 4 is a front elevational view of the earring of my design.

FIG. 5 is a rear elevational view of the earring of my design.

FIG. 6 is a rear elevational view of the earring of my design without the clasp.

FIG. 1

FIG. 2

FIG. 3

FIG. 4

FIG. 5

FIG. 6
